UNITED STATES PATENT OFFICE.

DAVID T. KENNEY, OF NORTH PLAINFIELD, NEW JERSEY, ASSIGNOR TO
SYLVANUS L. SCHOONMAKER, OF PLAINFIELD, NEW JERSEY.

DESIGN FOR A VALVE-BODY.

SPECIFICATION forming part of Design No. 31,715, dated October 24, 1899.

Application filed August 15, 1899. Serial No. 727,342. Term of patent 14 years.

To all whom it may concern:

Be it known that I, DAVID T. KENNEY, a citizen of the United States of America, residing in the borough of North Plainfield, county of 5 Somerset, and State of New Jersey, have invented and produced a new and original Design for a Valve-Body, of which the following is a specification, reference being had to the accompanying sheet of drawings, forming a part of this specification, in which—

Figure 1 is a perspective view of a valve-body constructed according to my design. Fig. 2 is a top view thereof.

As shown in the drawings, the leading and 15 essential feature of this design is a unitary valve-body composed of three substantially cylindrical sections placed one above the other, the upper section being closed at the top, the middle section being provided with 20 an opening at the side, and the lower section being provided with an opening at the bottom and a bracket at the side.

The valve-body is intended to inclose a valve for admitting water for the purpose of flushing plumbing-fixtures. In the particular form 25 shown in the drawings the upper section A has a squared projection *a* at the top, the middle section B has an opening *b* with a hexagonal flange at the side, and the lower section C has an opening *c* at the bottom and a bracket *d* at 30 the side.

Having described my design, what I claim, and desire to secure by Letters Patent of the United States, is—

The design for a valve-body herein shown 35 and described.

Signed by me in New York city, borough of Manhattan, State of New York, this 9th day of August, 1899.

DAVID T. KENNEY.
